UNITED STATES PATENT OFFICE

HARRY T. SHEARER AND CHARLES A. REIMSCHISSEL, OF WAYNESBORO, PENNSYLVANIA, ASSIGNORS TO LANDIS MACHINE COMPANY, OF WAYNESBORO, PENNSYLVANIA, A CORPORATION OF PENNSYLVANIA

DIE HEAD

Application filed December 27, 1928. Serial No. 328,635.

Our invention relates to die heads, and particularly to such die heads as are used on machines for cutting threads on bolts, screws, pipe, etc., using well-known tangential end sharpened chasers.

An object of the invention is to provide a two unit die head in which the front unit carries the cutters for producing the screw threads, and the rear unit constitutes the holding or driving unit; and to provide means whereby the front unit may float relative to the rear or holding and driving unit; and to provide further that the locking and driving members shall be independent of each other.

A further object is to provide a die head in which a floating action is secured to the locking and closing members and in which the locking members are contained in the floating unit and are not influenced by the holding or driving unit.

A further object of the invention is to provide a die head wherein the locking means is permitted to float with the thread cutting carrying means, and wherein the thread cutting carrying means and locking means are permitted to float relative to the die head holding shank.

A further object of the invention is to provide a die head having a floating front unit in which the locking mechanism is unaffected by the floating of the front unit.

A further object of the invention is to provide a die head composed of two units in which the front unit is driven by pins on the rear unit, so that the driving or resultant forces are carried by the pins instead of by the closing and locking means.

In constructions heretofore used, the locking pins bore the resultant forces of the cutters, such constructions being shown and described for example in Patent #1,631,556, to Harry T. Shearer and in Patent #1,692,514 to Samuel F. Newman and James G. Harper.

In constructions heretofore shown as in patent application #597,199 to Harry T. Shearer, the resultant forces of the cutters are carried by the trunnions and the worm connected to the driving shank or body whereas in this construction the resultant

forces are carried by pins in the holding or driving unit which are independent of the trunnions, locking pins or worms and at the same time this allows the opening action of the head to be the pull-off type or self-contained without relying on mechanical means such as spiders, yokes, cams, etc.

Further general objects are to provide a die head in which the cutting and locking members float relative to the driving shank or the driving member, and wherein misalignment of the work will not affect the locking means.

A further object is to provide a die head in which the resultant forces of cutting threads do not act through the locking means to the holding shank or driving member.

A still further object is to provide a die head employing tangential chasers and trunnions mounted in a body carrying the same, in which the unit carrying the cutting members aligns itself with the stock being cut, which stock can be eccentric with the shank or driving member without causing a rocking action upon the locking pins.

Further objects and advantages will become apparent as the description proceeds.

Referring to the accompanying drawings, which are made a part hereof and on which similar reference characters indicate similar parts.

Figure 1 is a lateral sectional view of the die head in locked closed position taken on line 1—1 of Fig. 2, and line 1—1 of Fig. 9.

Figure 2 is a section on line 2—2 of Fig. 1.

Figure 3 is a section on line 3—3 of Fig. 2.

Figure 4 is a section on line 4—4 of Fig. 2, showing the parts in open position.

Figure 5 is a section same as Fig. 4, showing the position of parts at the moment of opening.

Figure 6 is a section on line 6—6 of Fig. 2.

Figure 7 is a section on line 7—7 of Fig. 2, showing position of parts when the die head is closed.

Figure 8 is a section same as Fig. 7 showing position of parts when the die head is open.

Figure 9 is a face view of the die head.

In the drawings, numeral 10 indicates the

body member of the front unit of the die head having an opening ring 11 surrounding the front end, and an adjusting ring 12 surrounding the head body member just to the rear of the opening ring, said opening and adjusting rings having mounted therein opening means comprising a pin 13 on one ring and an abutment 14 on the other and a spring 15 acting against the pin on one end and against the abutment at the other, and adjusting means comprising a worm 16 and a worm gear 17 shown in Figures 1 and 2, same being shown and described in Patents Nos. 1,631,556 and 1,692,514. The body member 10 has a flange 18 made integral therewith, for holding the opening ring from forward movement on the head body. A ring plate 19 is secured to the rear face of the body member 10. Pins 20 are secured in body member 10 (Fig. 8) and serve to take the resultant force of threading and will hereinafter be more fully described. Chaser holders 21 carrying tangential chasers 22 are mounted upon trunnions positioned in bores 25 in the front head body member 10 and pivotally connected by means of pins 23 and block 24 to the opening ring 11 so that relative rotation of the opening ring and the front head body member will open and close the thread cutting jaws or chasers. The extended ends of trunnions 25 pass through the rear ring plate 19 and are secured by means of nuts 26 and lock screws 27 having a conical end which seats in a corresponding conical cavity in an end of the trunnion. A closing and locking ring 28 has mounted therein conical end pins 29 which extend through bores in the adjusting ring 12 into bushings 30 in the ring 11. Ring 28 is connected to the adjusting ring 12 by means of screws 31 which pass through bores in the ring 28 and screw into ring 12. These screws serve to limit movement of rings 28 in open position of the head. The front unit comprising all the above numbered and described parts, because of clearances 32, 33, 34, 35 and 35' is free to float in relation to the holding or driving member 36 and its component parts. It will be noted from an inspection of Figures 7 and 8 that clearances 35 and 35' are tapered. The holding or driving member 36 has a projecting flange 37 in which are mounted rods 38 with heads 39, said rods being held in place by removable pins 40. Surrounding rod 38 is a spring 41 lying between the head of the rod and ring plate 19, said springs being under compression at all times and tending to hold the holding and driving unit and the front unit together. Projecting from flange 37 is a flange 42 which in connection with flange 37 forms a surface against which the front unit rests. This surface is finished as at 43 at an angle to the axis of the member 36 to aid in the floating action of the front unit, flange 42 also forming a stop for

ring 28 when the remainder of the front unit moves forward in opening action. Member 36 has bores 44 to receiving pins 20 said bores being of such size as to make clearances 35 about the ends of pins 20, said bores and pins constituting the means for taking the resultant cutting forces.

The die head is in locked position as shown in Fig. 1. The driving and holding member 36 is fastened into a machine (not shown) performing the threading or other work in combination with the threading and the die head is advanced upon the work through the medium of member 36. The die head having cut the proper length of thread, member 36 is stopped in its axial travel by means (not shown) the chasers being engaged in cutting screw threads draw the front unit comprising body member 10, rings 11, 12, 19, 28 and all their integral parts forward causing a separation as at 45, Fig. 5, this separation being made against compression springs 41. The ring 28 being stopped in this travel by flange 42 withdraws pins 29 from the bushings 30 allowing the ring 11 to rotate which rotation causes ring 28 and pin 29 to assume positions as shown by Fig. 4. A return of the parts to locked thread cutting position is obtained by pushing ring 28 forward as shown in Fig. 1, springs 41 being of sufficient strength to overcome the load picked up by conical pins 29 in the rotating of ring 11 against springs 15.

It will be noted that as the opening action takes place springs 41 acting between the holding and driving member and the body member bring the body member to the same position as taken by this member when the die head is closed and that ring 28 takes a position independent of the remainder of the front unit as shown in Fig. 8, also that a clearance is provided at 46 to permit ring 28 to move a part of the movement which the front unit takes relative to the rear unit.

It will be obvious to those skilled in the art that various changes may be made in our device without departing from the spirit of the invention, and we, therefore, do not limit ourselves to what is shown in the drawings and described in the specification, but only as set forth in the appended claims.

Having thus fully described our said invention, what we claim as new and desire to secure by Letters Patent, is:—

1. A die head comprising a front body member and a rear body member, an opening ring, an adjusting ring mounted on the front body member and a closing and locking ring secured to said adjusting ring, conical pins mounted in said closing and locking ring, means permitting the front body member and said rings to move axially relative to the rear body member and means to limit the movement of said closing and locking ring relative to the rear body member and said ad-

justing ring whereby said conical pins lock and unlock the die head, substantially as set forth.

2. A thread cutting die head comprising a front unit having a body portion with an opening and an adjusting ring mounted thereon, a rear unit having a body portion with a closing and locking ring mounted thereon, conical pointed pins carried by the closing and locking ring, said pins engaging bores in the opening ring to hold the said ring in locked position, pins carried by the rear body member extending into bores in the front body member for driving the latter by the former, and resilient means for holding the front and rear body members together but yieldable to permit a slight axial movement therebetween, such movement permitting withdrawal of the points of the conical pins from the bushings in the opening ring to permit the ring to open, substantially as set forth.

3. A thread cutting die head comprising a front body member having opening and adjusting rings mounted thereon, a flange on the front portion of the body member, a plate secured to the rear of the body member for securing the rings upon the body member, a shank or holding member having a closing and locking ring mounted thereon, a flange on the front portion of the shank to limit the forward movement of the said closing and locking ring, a plurality of pins secured in the said shank and extending into bores in the front body member, springs surrounding said pins engaging heads on the pins at one end and the said plate on the rear of the front body member at the other end, said springs tending to hold the front body member and the said shank together, said closing and locking ring carrying conical pointed pins, the ends of which engage in bores in the opening ring to lock the opening ring in thread cutting position, substantially as set forth.

4. A thread-cutting die head comprising a front unit and a rear unit, the front unit carrying an opening ring, an adjusting ring and chaser holders carrying thread-cutting chasers, the rear unit carrying a closing and locking ring, conical pins mounted in said closing and locking ring for locking said head, clearances being provided between said closing and locking ring and the rear unit, driving pins in one unit, engaging sockets in the other unit to drive the front unit from the rear unit, said sockets having tapered clearances about said pins the first named and last named tapered clearances providing means whereby the front unit may have a pivotal movement in all directions relative to the rear unit to care for the misalignment of the work without affecting the position of the rear unit and without affecting the seating of said conical pins in said opening ring, and means for

securing an axial movement of the front unit relative to the rear unit for unlocking said head, substantially as set forth.

5. A thread-cutting die head comprising a front body member and a driving member, a plurality of rings surrounding said front body member and a ring on said driving member, clearances being provided between said last named ring and the driving member, chaser holders carrying thread-cutting chasers having parallel serrations on their faces, said chaser holders being mounted on the front body member and operably connected to one of said plurality of rings, the ring on the driving member carrying means engageable with that one of said plurality of rings which is operably connected to the chaser holders to actuate said chaser holders, driving pins carried by one of said body members and engaging sockets in the other body member, tapered clearances being provided about the ends of the pins in said sockets to permit said front body member to pivot on the driving member, said pins and bores transmitting the cutting thrust from the front body member to the driving member, substantially as set forth.

In witness whereof, we have hereunto set our hands at Waynesboro, Pennsylvania, this eleventh day of December, A. D. nineteen hundred and twenty-eight.

HARRY T. SHEARER.
CHARLES A. REIMSCHISSEL.
